US0D1078517S

(12) **United States Design Patent** (10) Patent No.: **US D1,078,517 S**
Chen (45) Date of Patent: ** Jun. 10, 2025

(54) **SMOKE LEAK DETECTOR**

(71) Applicant: **SOLARY ELECTRIC EQUIPMENT CO., LTD.**, Guangdong (CN)

(72) Inventor: **Zhixia Chen**, Guangdong (CN)

(73) Assignee: **SOLARY ELECTRIC EQUIPMENT CO., LTD.**, Zhuhai (CN)

(**) Term: **15 Years**

(21) Appl. No.: **29/993,604**

(22) Filed: **Mar. 16, 2025**

(51) LOC (15) Cl. **10-05**

(52) U.S. Cl.

USPC **D10/106.2**

(58) **Field of Classification Search**

USPC D10/46, 106.1, 106.2, 106.3

CPC G01M 3/025; G01M 3/38

See application file for complete search history.

(57) **CLAIM**

The ornamental design for a smoke leak detector as shown and described.

DESCRIPTION

FIG. 1 is a perspective view of a smoke leak detector showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the smoke leak detector and form no part of the claimed design.
